(57) **CLAIM**

The ornamental design for a double offset light used on trucks, as shown and described.

DESCRIPTION

FIG. 1 is a side-front perspective view of a double offset light used on trucks, showing my design;

FIG. 2 is a side-rear perspective view thereof

FIG. 3 is a front view thereof

FIG. 4 is a rear view thereof;

FIG. 5 is a right side view;

FIG. 6 is a left side view;

FIG. 7 is a top view; and,

FIG. 8 is a bottom view thereof.
